UNITED STATES PATENT OFFICE.

HUGO H. PLAUT, OF NEW YORK, N. Y.

DESIGN FOR AN ARTIFICIAL FEATHER.

SPECIFICATION forming part of Design No. 18,962, dated March 12, 1889.

Application filed January 19, 1889. Serial No. 296,948. Term of patent 3½ years.

To all whom it may concern:

Be it known that I, HUGO H. PLAUT, of the city, county, and State of New York, have invented and produced a new and original 5 Design for an Artificial Feather, of which the following is a specification, reference being had to the accompanying drawing, forming part thereof.

The drawing is a plan view representing a 10 design for artificial feathers, for which I desire to secure a patent.

The general outline of my design, when seen at a distance, approximates that of a curved and slender feather or leaf.

15 *a* is the central tapering rib, terminating with a small cross, *b*, at its lower end. A portion of the upper end of stem *a* is left without any lateral ornament. Each side of the lower half of stem *a* is provided with a series 20 of small crosses arranged as shown in the drawing. *c c c* are the said small crosses.

d d d are a series of smaller disks or facets arranged on each side of the central rib, between crosses *c c c*.

25 *e e e* are a series of curved ornaments

springing out from that portion of the rib between the stem and upper cross *c*. These curved ornaments are curled upward after the fashion of a shaving, and are arranged substantially as shown in the drawing. 30

f f f are a series of ornaments similar in shape to ornaments *e e e*. The upper end of each ornament *f* springs out of the left side of rib *a*, and the curled end of each ornament *f* mingles with or rests upon the left half of 35 stem *a*.

o o o are a number of small disks or facets scattered over the faces of ornaments *e e e* and *fff*.

What I claim is—

The design for artificial feather herein shown and described, the same consisting of rib *a*, crosses *b* and *c*, disks *d*, and curved ornaments *e e* and *f f*, substantially as set forth and described.

HUGO H. PLAUT.
